OSCILLATOR

Ollie M. Owsley, Haddon Heights, N. J., assignor
to Radio Corporation of America, a corpora-
tion of Delaware

Application June 29, 1935, Serial No. 29,026

9 Claims. (Cl. 250—36)

This invention relates to electron tube oscillators, particularly to oscillators operating on raw alternating current, and has special reference to grid biasing arrangements for oscillators of this general type.

Oscillators of the type described are useful in producing modulated voltages for aligning receiver equipment, calibrating frequency meters, and similar work where frequencies must be accurately and conveniently determined. They are also useful as radio beacons and for other purposes where an output of characteristic tone is required.

An object of the invention is to provide a novel and useful grid biasing arrangement for raw alternating current oscillators.

Another object of this invention is to maintain a negative potential on the grid of an electron tube generator, operated on raw alternating current, throughout the entire A. C. cycle.

A more specific object of the invention is to obtain a negative potential for the grid of a raw A. C. oscillator by a combination of two independently operating biases, to wit: self-bias by means of plate current drop in a cathode resistor during the positive plate current cycle and an alternating current voltage of negative polarity by means of a potential drop across an impedance, such as a transformer winding, and applied through a grid resistor, during the negative half cycle of plate current.

Another and important object of the present invention is to ensure optimum performance of a piezo-electric oscillator energized by raw alternating current.

In order to make the invention more clearly understood there are shown in the accompanying drawing means for carrying the same into practical effect, without limiting the improvements in their useful application to the particular embodiments, which, for purposes of explaining the inventive concept, have been made the subject of illustration.

Figure 1 is a circuit diagram of an electron tube oscillator, conveniently of the Hartley type, adapted to be energized by raw alternating current, and shows a grid biasing arrangement within the present invention.

Fig. 2 illustrates diagrammatically the grid biasing arrangement of the invention as applied to a piezo-electric oscillator energized with alternating current.

Referring now to Fig. 1, the particular form of oscillator which has been selected for illustration is a modified form of what is known as the

Hartley circuit. This oscillator comprises an electron discharge tube 1, preferably but not necessarily of the high vacuum thermionic type, having the usual grid, or control electrode 2 and a plate electrode 5. The tube is also provided with a preferably indirectly heated cathode 4 having a filamentary heater 3. The tube and its associated circuits are adapted to be energized with raw alternating current supplied from a convenient source of, say, 110-120 volts—50-60 cycles. The plate 5 is connected through a plate coupling coil 6 and lead 7 to one terminal 8 of the primary winding T_p of a transformer T which bridges the leads A. C. from the alternating current source, not shown. The filament 3 is energized by current induced in the secondary winding T_s of the transformer T.

The grid is connected by means of lead 12, condenser 13, grid coupling coil 14, and a short lead 12b to one terminal 10 of the secondary winding T_s , and by short lead 12a to the terminal 9 of the primary winding T_p opposite that (8) to which the plate lead 7 is connected.

Plate coil 6 and grid coil 14 are in energy transfer relation and are shunted by a variable condenser 15 which is provided for adjusting the frequency of the oscillations generated by the tube 1.

In accordance with the invention, two sources of grid biasing potential are provided. One of these, a grid resistor R_1 is connected between the grid 2 and one terminal 11 of the transformer secondary winding T_s across which one of the discrete biasing potentials is actually developed. The other grid biasing potential is developed by a self-bias resistor R_2 , shown shunted by a condenser C_2 which is of suitable value to pass radio frequency oscillations of the generated frequency. Resistor R_2 is connected as by 12b to the terminal 10 of the transformer winding T_s opposite that (11) to which the grid resistor R_1 is connected. The transformer windings T_p — T_s are relatively so poled that the grid 2 is prevented from going positive irrespective of the instantaneous polarity of the alternating current applied, from the A. C. source, to the anode 5.

From the foregoing it will be apparent that the objects of the invention are simply achieved by applying to the grid 2 an alternating current voltage in phase with that supplied to the plate 5 and adjusting the self-bias resistor R_2 to such a value that the negative bias generated thereby on the positive plate cycle exceeds the effective positive bias developed at that instant across 55

- $T_s - R_1$ by an amount to ensure proper operation of the device. Thus on the positive anode one-half cycle the grid is negative by the amount that the biasing voltage generated by R_2 exceeds the 5 alternating current grid potential, and on the negative anode one-half cycle the grid automatically becomes negative by the amount of bias developed across transformer secondary winding T_s .
- 10 One advantage of the dual biasing arrangement, of the present invention, over single, so-called "grid leak" biasing systems, is that the effects of grid loading (caused by zero or positive bias on the negative plate swing) is substantially 15 obviated, the device starts oscillating more readily at the beginning of each positive plate swing ensuring a substantially purely sinusoidal wave form; further, the efficiency of the device generally is increased.
- 20 The dual biasing arrangement of the invention is especially useful in starting and maintaining the generation of oscillations when used in connection with piezo-electric controlled oscillators energized by raw alternating current. This is so 25 because a piezo electric element itself requires appreciable time to start oscillations, i. e., it is not instantaneous in its operation. This "reluctance" or "time lag" is a property of the element per se and can be varied only to a small degree in the 30 cutting of the element.

With 60 cycle power on the plate of the associated circuit there is only 1/120th of a second available in which to build up positive oscillations. With usual biasing arrangements, from 35 the instant of zero plate voltage and during the negative half cycle, there is zero bias on the tube and high grid currents result. This results in "grid loading" which must be overcome before the crystal can again start oscillating. By the 40 time circuit conditions become normal, i. e., are in an electrical condition to permit vibration of the crystal, so much time (of the 1/120th second plate pulse) has been consumed that the crystal does not have sufficient time to start oscillating 45 before the plate voltage again falls to zero or some low voltage at which the circuit will not oscillate.

The above and other disadvantages inherent with existing A. C. actuated crystal controlled 50 oscillators are substantially obviated by the grid biasing arrangement of the present invention.

To convert the circuit of Fig. 1 into a crystal controlled oscillator it is merely necessary to insert a crystal having the desired frequency 55 characteristics and suitably mounted, in the grid circuit. Such an arrangement is shown in Fig. 2, which, with the exception of the addition of the crystal and a novel frequency change-over device, is similar in all respects to that illustrated in Fig. 60 1 and above described.

While the invention is not to be limited by the employment of a crystal of particular frequency response characteristic, it has been found, especially, when the oscillator is to be used for frequency calibration purposes, that there are certain definite advantages in employing a crystal cut in accordance with the principles set forth in copending application Serial No. 29,000 to Charles Baldwin and Samuel Bokovoy, filed June 70 29, 1935, Patent No. 2,073,046, granted March 9, 1937. Such crystals are cut to oscillate at but two fundamental frequencies, one of the frequencies bearing a multiple or other predetermined useful relation to the other. Thus, in Fig. 75 2 the crystal P may be assumed to be capable of

oscillating at a Y-mode frequency of 100 kilocycles per second and an X-mode frequency of 1000 kilocycles per second. The crystal is interposed between two electrode plates 33-33a and, one of which, 33, is connected to the grid 5 22 of tube 21 and the other electrode 33a is connected through a coil L_{21} to the filament at a point 39 on one side of the secondary winding T_s of the transformer T. There are two plate coils, L_{22} and L_{23} which are adapted to be selectively 10 coupled to coil L_{21} as by a switch S_1 . The mode or frequency at which the crystal P oscillates is determined by the constants of the tuned circuit with which it is associated, thus, for 100 K. C. oscillation switch S_1 is thrown to form a tuned 15 circuit including condenser C_{23} , coil L_{22} and all of L_{21} . For 1000 K. C. oscillation switch S_1 is thrown in the opposite direction and a circuit tuned to 20 1000 K. C. is formed by the combination of inductances L_{23} and a portion of L_{21} , shunted by 25 capacitor C_{25} . The necessary connection between L_{23} and L_{21} is provided by condenser C_{24} , though it may be constituted by the low impedance of the A. C. line. L_{22} and C_{23} now contribute little to the constant of this tuned circuit because of the extremely high impedance of these two units when in series.

As in Fig. 1, one of the dual biasing arrangements of the present invention comprises the transformer secondary winding T_s , to which grid resistor R_{21} is connected. The other grid biasing potential is developed by a self bias resistor R_{22} , across which is shunted a condenser C_{22} of suitable value to pass radio frequency oscillations 30 of the generated frequency. Resistor R_{22} is connected as by lead 32b to the terminal of the transformer secondary winding opposite that (31) to which the grid resistor R_{21} is connected. As set forth in connection with Fig. 1, the transformer windings are relatively so poled that the grid 35 22 is always maintained at a potential of a sign and intensity to ensure optimum performance. Appropriate values to achieve the hereinafter described operating characteristics are designated upon the circuit diagram. With circuit constants 40 of the values indicated, operation of the device is characterized by a high degree of overloading and distortion whereby a substantial series of harmonics, particularly useful for calibration purposes, is obtained. Thus, assuming that the 45 dial of a radio receiver is to be aligned, switch S_1 is thrown to form a tuned circuit including capacitor C_{25} , all of inductance L_{23} and a portion of L_{21} , whereby the crystal P will oscillate 50 at its X-mode fundamental frequency, i. e. 1000 55 K. C. The radio receiver is then tuned approximately to this frequency and, when the A. C. note is heard in the speaker, the dial is calibrated at that particular setting. If the switch is then thrown to its other position the note will still be 60 heard but it will be that produced by the tenth harmonic of the 100 K. C. Y-mode fundamental frequency of the crystal. The receiver dial is then slowly rotated and the note will fade only to reappear again at a dial setting corresponding 65 to a frequency 100 K. C. from the note first heard. It is thus possible to calibrate the dial exactly, as each multiple frequency is picked up by the receiver.

Various modifications of the above described 70 embodiments of the invention will suggest themselves to those skilled in the art. For instance, if it is desired to operate the oscillator at a plate voltage higher than that provided by a direct connection to the A. C. source, separate plate and 75

filament transformer secondary windings may be employed, in which case one terminal of the plate winding is preferably tied to a corresponding terminal of the filament winding—due regard being had to the phasing of the several windings.

5 Polyphase current may, of course, be utilized, if desired.

Although certain specific ways and means for accomplishing the objects of the invention have 10 been set forth, it will be understood that they have been given for purposes of explaining the inventive concept and should, therefore, not be construed as limitations to the scope of the invention.

15 What is claimed is:

1. In an oscillation generator, an electron discharge device having an anode, a cathode and a grid, a source of raw alternating current for said electrodes, and dual bias connections to said 20 alternating current source for deriving therefrom a biasing voltage for maintaining said grid at all times with respect to said cathode irrespective of the instantaneous polarity of the alternating current supplied to said anode.

25 2. The invention as set forth in claim 1 further characterized in this, that a piezo-electric element is provided intermediate said grid and cathode for controlling the frequency of the oscillations developed by said generator.

30 3. In an oscillation generator, an electron discharge device having a cathode, a grid and an anode, a source of raw alternating current for said electrodes, and means including a grid resistor and a transformer connected between said 35 grid and cathode for deriving a negative biasing voltage from said alternating current source for maintaining said grid negative with respect to said cathode throughout the negative half cycle of the alternating current supplied to said anode.

40 4. In an oscillation generator, an electron discharge device having a heater type cathode, a filament for said cathode, a grid and an anode, a source of raw alternating current for said anode and said filament, and dual means operatively connected to said alternating current source 45 and deriving a potential therefrom operative throughout both positive and negative cycles of said alternating current to prevent said grid from becoming positive with respect to said cathode.

50 5. In an oscillation generator, an electron discharge device having an anode, a cathode and a grid, a source of raw alternating current for said anode, two discrete sources of biasing potential, 55 and means determined by the instantaneous polarity of the alternating current applied to said anode for successively impressing said biasing potentials upon said grid to maintain it negative with respect to said cathode.

60 6. In an oscillation generator, an electron discharge device having an anode, a cathode and a grid, a source of raw alternating current for said anode, means for deriving discrete biasing po-

tentials from said current source and for successively applying the same to said grid to maintain it negative with respect to said cathode throughout the cycle of the alternating current applied to said anode.

7. In an oscillation generator, an electron discharge device having a cathode, a heater for said cathode, a grid and an anode, a tunable circuit connected to said anode, a source of raw alternating current, a transformer having primary and secondary windings, circuit connections from said windings for impressing current from said source upon said heater and upon said anode through at least a portion of said tunable circuit, a self-bias resistor, a connection 10 from said cathode through said resistor to one terminal of said secondary winding, a grid resistor and a connection from said grid through said grid resistor to the other terminal of said secondary winding, said transformer secondary 15 winding being relatively so poled that said grid is maintained negative with respect to said cathode throughout the cycle of the alternating current applied to said anode.

20 8. In an oscillation generator, an electron discharge device having a cathode, a heater for said cathode, a grid and an anode, a source of raw alternating current, a transformer having primary and secondary windings for impressing current from said source upon said heater and said 25 anode, a grid circuit connection between said grid and said transformer primary and from said primary to one terminal of said secondary winding, a self-bias resistor, a connection from said cathode through said resistor to the terminal of 30 said secondary winding to which said grid circuit is connected, a grid resistor, and a connection from said grid through said grid resistor to the other terminal of said secondary winding, said transformer windings being relatively so 35 poled that said grid is prevented from going positive with respect to the cathode irrespective of the instantaneous polarity of the current applied to the anode from said source.

40 9. In an oscillation generator, an electron discharge device having a plate, a cathode and a grid, a source of raw alternating current for said plate, a circuit between said grid and said cathode, a piezo-electric element in said circuit, the 45 electrical condition of said circuit during the 50 brief period which includes the instant of zero plate current and the negative half cycle of said alternating plate current being normally such as to inhibit optimum performance of said piezo-electric element, and dual means for deriving a 55 negative bias for said grid from said alternating current source and operative throughout said period to overcome said normal electrical condition of said circuit and including circuit connections for applying said bias between said cathode 60 and grid to thereby negatively bias said grid throughout said brief period.
